UNITED STATES PATENT OFFICE.

GEORGE H. GOLDSMITH, OF OLD ORCHARD, MAINE, ASSIGNOR TO SACO-LOWELL SHOPS,
OF BOSTON, MASSACHUSETTS, A CORPORATION OF MASSACHUSETTS.

BOBBIN-HOLDER.

1,182,557.

Specification of Letters Patent.

Patented May 9, 1916.

Application filed July 3, 1914. Serial No. 848,934.

To all whom it may concern:

Be it known that I, GEORGE H. GOLDSMITH, of Old Orchard, in the county of York and State of Maine, a citizen of the United States, have invented a new and useful Improvement in Bobbin-Holders, of which the following is a full, clear, and exact description, reference being had to the accompanying drawings, forming a part of this specification, in explaining its nature.

The present invention relates to an improvement in bobbin holders particularly adapted for warp-wound bobbins.

Among the essential objects of the invention is to provide an improved means for supporting the follow wires; to provide whereby the follow wires may bear against the bobbin with increased friction as the bobbin grows lesser in diameter, and to provide also whereby variation may be obtained in the draw of the thread after leaving the bobbin held by the holder.

The invention can best be seen and understood by reference to the drawings in which—

Figure 1 is a plan of the bobbin holder. Fig. 2 shows the holder partly in side elevation and partly in longitudinal vertical section. Fig. 3 is a section on the line 3—3 of Fig. 2, and Fig. 4 is a forward end elevation of the holder.

Referring to the drawings: 1 represents a bracket attachable to a rod 2 upon which the holder is mounted, attachment being secured in the usual manner. The bracket 1 is provided with forwardly and upwardly projecting arms 3 and 4, respectively. Secured to the arm 3 is a bobbin plate 5 on which the bobbin rests. The upwardly-projecting arm 4 of the bracket is provided with a forwardly-projecting portion or butt 6 having openings therein. Extending through these openings to turn within the butt are rods 7, 7. These rods are substantially parallelly arranged and project forward from the butt to extend over the face of the bobbin plate. Secured to the rods 7, 7 are the follow wires 8, 8 which swing over the face of the bobbin plate in the usual manner as the rods carrying the same turn within the butt. The rods 7, 7 extend through the openings in the butt and each rod is held against endwise displacement by means of a yoke 9 which straddles the butt to bear loosely against the forward and rear ends thereof and which yoke is se-

cured to the rod. In other words, each yoke is provided with inwardly-turned ends or flanges 10, 10 having a loose bearing, respectively, against the forward and rear ends of the butt. The rods extend through these turned ends of the yokes and the yokes are secured to the rods by means of binding screws 11 tapped through the rear ends of the respective yokes and bearing against the rods.

The yokes 9 are overweighted in the sense that they are provided with overweighted sides 12 which lap respectively around the respective sides of the butt (see Fig. 3). The over weighting of the sides of the yokes has the effect of over weighting the rods 7, 7 to which the respective yokes are secured and which turn with the rods. Moreover, the lateral disposition of the weighted sides 12 of the yokes with relation to the rods is such as to exert an influence to turn the follow wires carried by the rods inwardly, this influence being at a minimum when the follow wires are in a maximum outward position and gradually increases as the wires are moved inwardly. This is the normal action although of course considerable variation may be obtained depending upon the manner in which the yoke is over weighted and set upon the rod.

The general operation of the holder above described is substantially like that of any holder excepting that it possesses many advantages both structurally and in detail of operation. Primarily a very substantial axial support is obtained for the follow wires which admits also of their proper location through adjustment of the rods 7; in other words, by simply loosening the binding screws 11 the rods 7 and follow wires may be moved adjustably and their positions determined and afterward maintained by again tightening the set screws. By means of the laterally-overweighted yokes the frictional bearing of the follow wires against the bobbin is gradually increased as the bobbin lessens in diameter, thereby tending at all times to impart a proper frictional retardation to the unwinding of the bobbin. In Fig. 4 the over weighted members are shown exerting substantially their maximum pressure against the sides of the cop, indicated in dotted lines, and from which it should be understood the thread is nearly unwound, the

view being simply illustrative. A considerable variation in the degree of frictional retardation is effected simply by adjusting the position of the overweighted sides of the 5 yokes with relation to the rods, and such adjustment may be obtained by first loosening the binding screws 11 and after the adjustment is obtained again tightening said screws. A still further adaptability of the 10 structure resides in the fact that the thread as it is unwound may be led from beneath the side of the draw wires in the usual manner or be passed upwardly from the bobbin around either of the rods 7. That is, the 15 structure is capable of a side draw or a center draw of the thread, a center draw being preferable under some circumstances. In this connection it is to be observed by reference to Fig. 1 that the bobbin holder is 20 mounted at an angle with relation to the right line of the rod 2 which tends to give a cross traverse to the thread as it is being unwound from the bobbin, which is an advantage in a bobbin holder, and this effect is 25 obtained whether the thread draws from under one of the follow wires with a side draw or has a center draw over one or the other of the rods 7.

Having thus fully described my invention, I claim and desire to secure by Letters Patent of the United States:—

1. A bobbin holder comprising in combination a bobbin-supporting plate, an attaching bracket bearing said plate and having 35 an upwardly-projecting arm carrying a butt with openings through it, rods extending through said openings to turn within the butt and projecting forward therefrom over said bobbin-supporting plate, means

for securing said rods against endwise displacement with relation to said butt, and follow wires carried by said rods. 40

2. A bobbin holder comprising in combination a bobbin-supporting plate, an attaching bracket bearing said plate and having 45 an upwardly-projecting arm carrying a butt with openings through it, rods extending through said openings to turn within the butt and projecting forward therefrom over said bobbin-supporting plate, follow wires 50 carried by said rods, and laterally-overweighted means fixed to said rods and co-operating with said butt to prevent endwise displacement of the rods with relation to the butt. 55

3. In a bobbin holder, the combination with a bobbin-supporting plate, of an attaching bracket, an upwardly-projecting arm carrying a butt, rods mounted to turn within said butt, yokes extending over said 60 butt to connect with said rods for holding the same against endwise displacement, and follow wires carried by said rods.

4. In a bobbin holder, the combination with a bobbin-supporting plate, of an attaching bracket having an upwardly-projecting arm carrying a butt with openings therein, rods extending through said openings to turn within said butt, laterally-overweighted yokes straddling said butt and connecting with said rods for holding the same against endwise displacement, and follow wires carried by said rods. 65 70
